UNITED STATES PATENT OFFICE.

MORESS S. FINKELSTEIN, OF NEW YORK, N. Y.

ANTIREFILLING BOTTLE-STOPPER.

1,216,428.

Specification of Letters Patent. Patented Feb. 20, 1917.

Application filed December 2, 1914. Serial No. 875,089.

To all whom it may concern:

Be it known that I, MORESS S. FINKELSTEIN, a citizen of the United States, and a resident of New York city, in the county of 5 New York and State of New York, have invented certain new and useful Improvements in Antirefilling Bottle-Stoppers, of which the following is a specification.

This invention relates to bottle stoppers, 10 more particularly stoppers which when applied to bottles render the latter non-refillable.

The principal object of this invention is to provide a stopper of comparatively simple and inexpensive construction which may be applied to any bottle so as to render the latter non-refillable and thus protect the public from the substitution of spurious or inferior goods by unscrupulous parties, 20 while the dispensing of the liquid from the bottle may be accomplished with ease and despatch.

A further object is to provide a stopper of the above character all the parts of which 25 may be stamped out of sheet metal, easily assembled, and readily applied to bottles so as to remain permanently affixed thereto, their removal being only capable of accomplishment by the breaking of the bottle.

30 Further objects and advantages arising from the construction, arrangement, and combination of parts will more fully appear from the following detailed description, and the features of novelty will be particularly pointed out in the claims.

In the drawings,

Figure 1 is a vertical section of my improved bottle stopper shown applied to a bottle.

40 Fig. 2 is a transverse section taken along line 2-2 of Fig. 1.

Fig. 3 is a similar section taken along line 3-3 of Fig. 1.

45 Fig. 4 is a vertical section of a modified form of my invention also shown applied to a bottle.

Fig. 5 is a view of the form shown in Fig. 4 illustrating the position of the parts in their dispensing positions.

50 Referring in detail to Figs. 1, 2, and 3, my improved stopper comprises a head 10 provided with a chamber 11. Extending from the edge of the head is an annular flange 12, and suitably secured to the flange is a closure 13 for the chamber. Axially depending from the closure is a sleeve 14,

which is provided at its lower end with an annular flange 15. An outer sleeve 16 envelops the sleeve 14, is of a length less than that of the latter, and is of a diameter such 60 that the sleeve 14 is readily reciprocable therein. The outer sleeve 16 is provided at its upper and lower ends with annular flanges 17 and 18, respectively. The lower flange 18 is of a width such that it falls 65 short of contacting with the neck of the bottle when the stopper is inserted therein. The upper flange 17, however, is of a width to overlap the bead of the bottle and rest thereon. By reason of the two flanges 70 extending from the outer sleeve 16 there is formed about the latter an annular channel in which may be packed a mass of properly prepared cement 19 or other suitable substance when the stopper is to be applied to 75 the bottle, and after the cement has become hardened and set the stopper will be effectively and permanently affixed thereto, as will be readily understood.

The upper edge of the inner sleeve 14 is 80 slightly raised above the general level of the closure 13, and a small annular portion 13^a of the latter about the sleeve is also raised angularly from the surface of the closure to meet the edge of the sleeve 14. 85 The edge of the latter is thus comparatively sharp, and therefore constitutes a good seat for the valve head 20 of the valve 21 which is slidably held in the sleeve 14. The lower end of the valve is provided with a baffle 90 plate 22 of a diameter preferably greater than that of the valve, and adjacent the baffle plate and valve head the valve is provided with a plurality of ports 23 and 24, 95 respectively.

The chamber 11 is provided with a plurality of discharge openings 25 formed at spaced points in the closure 13. These openings are preferably circular, and in order that the chamber may be effectually 100 sealed while the contents of the bottle is not being dispensed, I form a corresponding number of circular teats 26 in the flange 17 of the outer sleeve which register with the openings and upon which the closure 13 105 seats. The teats also serve the further function of preventing the turning of the head 10 while the bottles are being shipped. This is very important, as in shipping bottles of this character the stopper and a portion of 110 the neck adjacent thereto are usually wrapped in tin foil or other similar ma-

terial, and if the stopper were rotatable instead of fixed there would be danger of the foil becoming torn by an inadvertent twisting of the stopper, whereupon the latter becoming released, the contents of the bottle might spill out.

As clearly illustrated in Fig. 1, the ports 24 in the valve are normally out of communication with the chamber 13 as the valve head 20 rests upon the edge of the sleeve 14. The contents of the bottle is, therefore, effectively sealed from the atmosphere thereby, as well as by reason of the fact that the chamber 11 is maintained securely sealed as above described.

When the bottle is tilted into its dispensing position the head 10 will move forward until the flange 15 in the inner sleeve 14 abuts the flange 18 in the outer sleeve 16. The valve 21 simultaneously advances until its head 20 strikes the inside surface of the head 10, the valve being of such length that there remains a small opening between the flange 15 and the baffle plate 22. The head 10 having advanced clear of the teats, the ports 24 having moved clear of the sleeve 14, and there remaining an opening between the flange 15 and the baffle plate 22, the liquid in the bottle will have free passage through the ports 23, valve 21, ports 24, chamber 11, thence through apertures 25 into the receiving receptacle. Upon being again placed in a vertical position, the various parts will immediately slide back into their normal position, and if any drops of the liquid through capillary attraction or otherwise should remain in the chamber 10 the same would be retained therein and be prevented from trickling down the sides of the bottle by reason of the effective seal formed by the teats.

It is clear that any attempt at refilling the bottle would fail, since there is no direct path by which the liquid could be forced. The liquid would have to travel by a tortuous route—first into the chamber and then into the valve and then through the small openings 23 at the lower end of the valve. This alone would render refilling difficult; but further difficulties are presented. In order to have any possible chance of success in refilling the so-called "non-refillable" bottles, the liquid must be forced in under pressure. Thus, if a stream of the liquid should succeed in entering the valve when the bottle is kept in an inverted position, the pressure of the liquid upon the baffle plate 22 would cause the valve head 20 to seat upon the sleeve 14, thus closing the valve. Further, since it is necessary to provide an outlet for the air contained in the bottle in order that the latter may be filled with the liquid, this proves to be another insurmountable difficulty, for the chamber 11 upon becoming filled with liquid, as it necessarily

would under the circumstances, becomes an effectual seal, preventing all egress of air.

In Figs. 4 and 5 I have illustrated a modified form of my invention, the principle being substantially the same as in the preferred form above described. Thus the head 30, which may be of porcelain or other suitable material, is provided with a circular chamber 31 at its center. An upwardly flaring tube or sleeve 32, terminating at its upper end with an annular flange 33, which is adapted to rest upon the bead of the bottle, communicates with the chamber 31, and is securely embedded within the head 30. At the lower end of the tube 32 is formed an annular flange 34. At substantially the junction of the flange 33 and the flaring portion of the tube 32 there are formed a plurality of spaced apertures 35 communicating with the chamber 31. Directly below these apertures a valve 36, having a stem 37 depending therefrom, normally is seated in the tube, this being by reason of the upwardly flaring character of the latter. The other end of the stem 37 is provided with a circular baffle plate 38 of a diameter preferably somewhat greater than that of the tube 32.

Embracing the tube 32 is a sleeve 39 of a contour corresponding with that of the tube and of a length less than that of the latter. The sleeve 39 is provided at its upper and lower ends with annular flanges 40 and 41, respectively, constituting a channel in a manner analogous to the figure above described, wherein cement or other suitable substance may be packed for securely affixing the stopper to the bottle, as pointed out above.

When the bottle is tilted to its dispensing position, as shown in Fig. 5, the valve 36 moves forward past the apertures 35 and abuts the wall of the chamber 31, the head 30 also moving forward until the flange 34 upon the tube 32 abuts the flange 41 of the sleeve 39. The stem 37 being of such length that the plate 38 cannot close the tube 32, the liquid may freely flow up into the latter, through the apertures 35, and into the receiving receptacle.

To prevent the head 30 from rotating, I form lugs 42 upon the flange 40 of the sleeve 39, which register with the apertures 35 and seal the same. However, in this form there could be no trickling of the liquid down the outside of the bottle in any case by reason of any residue of drops in the chamber, as is readily apparent.

In this form of my invention, if attempt were made to refill the bottle by directing a stream of liquid through the tube, the liquid impinging upon the plate 38 would cause the valve to drop below the apertures 35, thus sealing the bottle.

It is clear, therefore, that I have provided

5 a bottle stopper which may readily be applied to any bottle whatsoever and render the same non-refillable. The stopper allows the ready discharge of the contents of the bottle, and when the contents is not being dispensed all openings and ports are effectually sealed, thus preventing evaporation, fermentation, or other deterioration due to contact with the atmosphere. It presents a
 10 compact, neat appearance, and does not unduly enlarge the size of the bottle. The head of the stopper, which is all that is disposed exteriorly of the bottle may be embellished in any manner desired so as to ornament the latter. It may be all stamped out of sheet metal, so that the cost of production would be very low.

Although I have shown merely two embodiments of my invention, it is obvious that 20 various other modifications might be made without departing from the spirit thereof.

Having thus described my invention, I claim:

1. An anti-refilling stopper for bottles, 25 comprising a movable head adapted to cover the mouth of the bottle, a sleeve depending from said head and movable therewith, an outer sleeve surrounding said depending sleeve and adapted to be permanently affixed 30 to the neck of the bottle, and a reciprocating valve within the depending sleeve for opening and closing the interior of the bottle to the atmosphere, said valve being provided with a baffle plate at the interior end thereof 35 whereby the valve is forced upon its seat when it is attempted to direct a stream of liquid within the bottle to refill the same, said head and valve being adapted by their own weight to uncover the mouth of the bottle and expose the interior thereof to the atmosphere when the bottle is tilted.

2. An anti-refilling stopper for bottles, 45 comprising a hollow head having discharge openings and adapted to cover the mouth of the bottle, a sleeve depending from said head and communicating therewith, an outer sleeve loosely surrounding said depending sleeve and adapted to be permanently affixed to the neck of the bottle, and a double headed 50 valve adapted to reciprocate within the depending sleeve to open and close communication between the interior of the bottle and the head, the bottom head forming a baffle plate for causing the upper head to close the discharge opening in the first mentioned sleeve.

3. An anti-refilling stopper for bottles, 60 comprising a hollow head having discharge openings and adapted to cover the mouth of the bottle, a sleeve depending from said head and communicating therewith, said openings being sealed when the head is resting upon said mouth, an outer sleeve loosely surrounding said depending sleeve and adapted to be 65 permanently affixed to the neck of the bottle,

a double headed valve adapted to reciprocate within the depending sleeve to open and close communication between the interior of the bottle and the head, the bottom head forming a baffle plate for causing the upper head to close the discharge opening in the first mentioned sleeve and means for restricting the longitudinal movement of the depending sleeve within the outer sleeve. 70

4. An anti-refilling stopper for bottles, 75 comprising a head adapted to cover the mouth of the bottle, a sleeve depending from said head, an outer sleeve movably mounted upon said depending sleeve and adapted to be permanently affixed to the neck of the bottle, a valve adapted to reciprocate within the depending sleeve for opening and closing the interior of the bottle to the atmosphere, and means for preventing rotation of the head in either direction when the latter is seated upon the mouth of the bottle. 80

5. An anti-refilling stopper for bottles, 85 comprising a head having a chamber, said chamber having discharge openings, a sleeve depending from said chamber and communicating therewith, an outer sleeve movably mounted upon said depending sleeve and adapted to be permanently affixed to the neck of the bottle, and projections upstanding 90 from the outer sleeve to register with the discharge openings whereby the head is prevented from rotating when the latter is resting upon the mouth of the bottle and the chamber is sealed from the atmosphere. 95

6. An anti-refilling stopper for bottles, 100 comprising a head having a chamber, said chamber having discharge openings, a sleeve depending from said chamber and communicating therewith, an outer sleeve movably mounted upon said depending sleeve and 105 adapted to be permanently affixed to the neck of the bottle, a valve adapted to reciprocate within the depending sleeve to open and close communication between the interior of the bottle and the chamber, and upstanding projections upon the outer sleeve adapted to register with said discharge openings whereby the head is prevented from rotating when the latter is resting upon the mouth of the bottle. 110

7. An anti-refilling stopper for bottles, 115 comprising a head having a chamber, said chamber having discharge openings, a sleeve depending from said chamber and communicating therewith, an outer sleeve movably 120 mounted upon said depending sleeve and adapted to be permanently affixed to the neck of the bottle, a valve adapted to reciprocate within the depending sleeve to open and close communication between the interior of the bottle and the chamber, projections upon the outer sleeve adapted to register with said discharge openings whereby the head is prevented from rotating when the latter is resting upon the mouth of the bottle. 125

bottle, and means for restricting the longitudinal movement of the depending sleeve within the outer sleeve.

8. An anti-refilling stopper for bottles, comprising a head adapted to rest upon the mouth of the bottle, a sleeve depending from said head, an outer sleeve loosely surrounding said depending sleeve and adapted to be permanently affixed to the bottle, a sleeve valve adapted to reciprocate within said depending sleeve for opening and closing the interior of the bottle to the atmosphere, and a baffle plate upon the lower end of the valve whereby the valve is forced upon its seat when a stream of liquid is directed into the bottle in an attempt to refill the same.

9. An anti-refilling stopper for bottles, comprising a head adapted to rest upon the mouth of the bottle, said head having a chamber, a sleeve depending from said head and communicating with the chamber, an outer sleeve movably mounted upon said depending sleeve and adapted to be permanently affixed to the bottle, a sleeve valve adapted to reciprocate within said depending sleeve for opening and closing communication between the chamber and the interior of the bottle, said valve having a head adapted to seat upon the upper edge of the depending sleeve when the bottle is held upright and unseating therefrom when the bottle is tilted, said depending sleeve being longer than the outer sleeve and provided

with a stop to restrict its longitudinal movement, and said valve being longer than the 35 depending sleeve.

10. An anti-refilling bottle stopper, comprising a head having a chamber, the latter having discharge openings, a sleeve depending from said head and communicating with said chamber, an outer sleeve slidably surrounding said depending sleeve and adapted to be permanently affixed to the neck of the bottle, said depending sleeve being longer than the outer sleeve and provided with a flange at its lower end to restrict the forward movement of the head when the bottle is tilted, a sleeve valve provided with a head at each end, said valve being adapted to reciprocate within said depending sleeve, the upper valve head normally seating upon the upper edge of the depending sleeve to close communication between the interior of the bottle and the chamber, there being ports in the valve adjacent both heads, and the 50 valve being of a length such that the lower head does not seat upon the lower edge of the depending sleeve when the valve is at its extreme forward position.

Signed at New York city, in the county 60 of New York and State of New York, this 1st day of December, A. D. 1914.

MORESS S. FINKELSTEIN.
